UNITED STATES PATENT OFFICE.

WILLIAM H. BRIDGMAN, OF BROOKLYN, NEW YORK.

DESIGN FOR A RAZOR-WIPER.

SPECIFICATION forming part of Design No. 24,635, dated August 27, 1895.

Application filed July 27, 1895. Serial No. 557,390. Term of patent 14 years.

To all whom it may concern:

Be it known that I, WILLIAM H. BRIDGMAN, a citizen of the United States, residing in the city of Brooklyn, in the county of Kings and State of New York, have invented and produced a new and original Design for Razor-Wipers, of which the following is a specification, reference being had to the accompanying drawings, forming a part thereof.

Figure 1 is a perspective view of a razor-wiper of my design. Fig. 2 represents a transverse sectional view of the same, and Fig. 3 a longitudinal section of the same.

A razor-wiper of my design presents in its face a series of parallel ridges A A, and the leading feature of the design is the form of

these ridges, the transverse section of the said ridges being angular, as shown at *a* in Fig. 2, and the longitudinal profile, consisting of a series of saliently-curved inclines *b b*, connected, as shown in Fig. 3, by abrupt projections *c c*, the said projections in the several ridges ranging with each other in lines transverse to the ridges, as shown in Fig. 1.

What I claim is—

The design for a razor-wiper, substantially as herein shown and described.

WILLIAM H. BRIDGMAN.
